UNITED STATES PATENT OFFICE.

BERNHARD VOLKMAR, OF NEW YORK, N. Y., ASSIGNOR TO VOLKMAR AUTO STARTER COMPANY, A CORPORATION OF NEW YORK.

STARTER FOR INTERNAL-COMBUSTION ENGINES.

1,037,376.

Specification of Letters Patent. Patented Sept. 3, 1912.

Application filed June 17, 1910. Serial No. 567,388.

To all whom it may concern:

Be it known that I, BERNHARD VOLKMAR, a citizen of the United States, residing at the borough of Bronx, in the city, county, 5 and State of New York, have invented certain new and useful Improvements in Starters for Internal-Combustion Engines, of which the following is a specification, reference being had therein to the accompanying 10 drawings, which form a part thereof.

My invention relates to starters for internal combustion engines, and more particularly to a type thereof adapted to turn the engine over to insure the firing of the 15 initial charge, and be re-set by the subsequent operation of the engine.

One object of my invention is to provide a spring actuated starting device embodying few parts of simple design, wherein the 20 driving member, when released, will, under the control of its spring, turn the engine over a sufficient number of times to insure the compression and ignition of a charge, and thereafter be automatically locked to 25 permit the rewinding of the spring, the engine shaft, while being normally under the control of said driving member in starting, being free to rotate independently thereof.

30 A further object is to provide a spring actuated starting device wherein the spring drum will be normally locked to absorb the reaction of the spring while being capable of rotation under the control of the engine, 35 to rewind the spring.

A still further object is to provide a starting device wherein the rewinding of the spring will be accomplished by a minimum application of the engine power, to reduce 40 the load upon the engine when starting, and thus avoid liability of such an overload on the engine as would tend to cause it to stop after the actuation of the starter, while initiating the rewinding of the spring at 45 substantially the instant when the driving member ceases to act upon the driven member.

A still further object is to provide a starting device, wherein the mode of application 50 of engine power in rewinding will be such as to avoid a constant load upon the engine.

A still further object is to provide a starting device wherein that portion of the rewinding mechanism in operative relation

to the engine shaft or driven member, will have a constant operation, while the means actuated thereby for rewinding the spring will be automatically disconnected from said portion when the spring is rewound to 60 the desired extent, to relieve the said spring from excessive strains.

A still further object is to provide a starting device, wherein the extent to which the 65 spring is rewound will be automatically determined by the number of revolutions of the driving member upon the actuation of the starter.

A still further object is to provide a starting device wherein the driving member will 70 be held against any reversal of its direction of rotation under a "kick-back" from the engine.

A still further object is to provide in a starting device of this character a manually 75 operative starting crank to enable the user to start the device by hand if the engine does not respond to the mechanical starter, the construction of the starter being such as to serve as a safety appliance for preventing a "kick-back" of the crank and resultant injury to the user.

A still further object is to provide a starting device wherein, if desired, the tripping mechanism may be so constructed as to cause the driving member to rotate a fixed predetermined number of times, and thus avoid any possibility of such a re-setting of the tripping device as would prematurely lock 80 said driving member.

A still further object is to provide a 85 starter wherein the power of the spring will be applied to the engine shaft, or other driven member, and the spring will be rewound from the engine shaft, or other driven member, without employing gears or other toothed mechanisms thus eliminating all possibility of the starter being gotten out of order by a too sudden application of 90 power in either direction.

A still further object is to provide a 95 starter wherein the various parts will be instantly and automatically released or locked as required at any stage of the operation of the starter.

A still further object is to provide a 100 starter which will be so constructed as to cause all of the holding or feeding parts to have a minimum quantity of wear through the repeated operations of the de- 105

vice, and to automatically readjust themselves to compensate for wear without a loss of efficiency.

A still further object is to provide a 5 starter which may be released or tripped from the driver's seat without any substantial effort on the part of the driver, and which when released, will turn the engine over a sufficient number of times to insure 10 the initial starting thereof and thereafter the resetting within a sufficiently short period (say from one half to one minute), to permit the reapplication of the power at any reasonable time thereafter.

15 A still further object is to provide a starter of this character, wherein the spring power may be increased if desired, by the addition of further spring elements without substantial alteration in the mechanisms of 20 the starter.

25 A still further object is to provide a device wherein the number of rotations of the driving member, upon the release thereof, may be varied at the will of the operator to 30 adapt the starter to different horse power machines and conserve spring energy.

35 A still further object is to provide a starter which will be capable of actuation without material noise from moving parts. And a 40 still further object is to provide a starter which may be inexpensively produced, and will effectively apply to the engine the power necessary to turn the engine over a sufficient number of times to insure the compression and ignition of the initial charge.

The invention consists primarily in a starter for internal combustion engines embodying therein a spring actuated driving member, a driven member, a clutch acting solely by friction carried by one of said members and engaging the other when said driving member is operative, said clutch being inoperative when said driving member is locked, whereby said driven member will be rotated with said 45 driving member and may rotate independently thereof, means locking said driving member, means whereby said locking means may be released, and a rewinding mechanism operative from said driven member; 50 and in such other novel features of construction and combination of parts as are herein-after set forth and described and more particularly pointed out in the drawings hereunto appended.

55 Referring to the drawings:—Figure 1 is a vertical section through a starter embodying my invention; Fig. 2 is a view on line 2—2 of Fig. 1; Fig. 3 is a detailed view of one of the friction ratchets, and Fig. 4 is a 60 detailed view of the star wheel and tripping mechanism.

Like letters refer to like parts throughout the several views.

In the embodiment of my invention, 65 shown in the drawings, *a* indicates a plate

adapted to be attached to the under frame of the machine adjacent to the forward end of the engine shaft. Carried by this plate *a* is a casing *b*, said plate and said casing carrying the operative parts of the starter. Mounted within the casing *b* is a spring drum *c* preferably provided adjacent to one edge thereof with a bearing *c'* engaging the casing *b*. The drum *c* is provided with a cover *c''*. Centrally of the drum *c* is a driving member *d* preferably in the form of a hollow arbor, the springs *e* being mounted in said drum with the opposite ends thereof secured respectively to the arbor *d* and drum *c*. Any desired number of springs *e* may 70 be used, according to the horse power of the engine in connection with which the starter is to be used, a partition *e'* separating these springs when a plurality of such are used, and such multiplication of springs requiring merely an increase in the dimensions of the casing, drum and arbor. By this construction of spring drum, the springs may be 80 readily assembled in the drum, and may be readily removed in case of breakage to permit the substitution of new springs. One end of the arbor *d* is journaled in the drum *c*, and casing *b*, and the other end thereof is stepped as at *d'* and bears in an opening in the drum *c*. Mounted in the plate *a* and arbor *d* is the driven member *f* which is 85 adapted to form a part of, or be coupled to, the engine shaft so as to transmit the rotary movement of the arbor *d* to the said shaft. Preferably, to compensate for loss of alignment in the engine shaft and the driven member *f*, owing to the manner of attachment of the starter to a car, I preferably 90 connect the member *f* to the engine shaft by means of a universal coupling indicated at *f'*, the engine shaft proper being indicated at *f''*. 95

To secure the rotation of the driving member or arbor *d* by the spring *e*, it is necessary to provide the drum *c* with a resistance means sufficient to absorb the re-action of said spring or springs, such means, however, being necessarily so constructed and arranged as to permit the free rotation of said drum to accomplish the rewinding of the spring, said arbor itself being necessarily equipped with a resistance means or locking member for the purpose of normally holding said arbor inoperative to permit the winding of the spring and the holding of the spring tension. 100

The resistance or holding means for the drum *c* comprises the circular brake rim *g* attached to, or forming an integral part of the head of the drum *c*, said rim being concentric with the driving member or arbor *d*. Mounted upon this rim is a friction pawl *h* consisting of a metal block having therein a channel of a width approximating the thickness of said rim *g*. Carried by the 105 115 120 125 130

plate *a* is a fixed stop *h'* against which the lower portion of the said friction pawl *h* bears when in the locked position, a spring *h²* acting to normally set said pawl in the locking position. It will be observed by this construction that when force is applied to the drum in a direction through the pawl *h* toward the stop *h'* or toward the spring, the said force will so lock said pawl upon said rim as to offer a resistance proportionate to the force applied, and thus, under no circumstances, permitting the drum to rotate in that direction. If, however, the force be applied in the opposite direction, it will carry the pawl away from the stop, tensioning the spring *h²*, and permit the drum to rotate freely in the opposite direction, the spring *h²* when the rotary movement of said drum ceases, instantly restoring the pawl to its former, set position.

The arbor or driving member *d* within the rim *g* is provided with a similar brake rim *i* but of lesser diameter coöperating with which is a similar friction pawl *j* pivotally secured to the driven member *f* at the lower end thereof, the spring normally setting said pawl, being attached to, and movable with, said driven member. The pivotal connection between the pawl *j* and the member *f* will ordinarily merely consist in the beveling of the lower edge of the pawl *j*, and the seating of this beveled end in a recess having oppositely disposed inclined walls of a pitch sufficient to permit that slight oscillation of the pawl *j* necessary to permit the engagement and disengagement thereof from the brake rim *i*. It will be observed that by this construction, force applied upon the pawl *j* toward the spring *j'* will set the pawl relative to the rim *i* offering a resistance equaling the force exerted by the spring, and thus cause the rotary movement of the driving member or arbor *d* to impart a similar movement to the driven member *f*, the movement of the said member *f* at a speed greater than that of the arbor *d* serving to release the pawl *j* and carry this pawl about the brake rim *i* without any braking action occurring between these two members. It will be observed, however, that the instant when the speed of the arbor *d* exceeds that of the engine shaft, or the driven member *f*, the parts *i j* will set irrespective of the position of these parts, and that when the pawl *j* is running idly, or is locked upon the brake rim *i*, the action of the spring *j'* will be such as to avoid any substantial wear upon either of these parts.

The pawls, or other friction clutch members *h* and *j* with their coöperating members *g* and *i* take care of the action and reaction of the spring or the springs *e*, it being only necessary to provide means for controlling the operative moment or release of

the driving member and means re-setting the starter through the rewinding of the drum, such means constituting a reversal of the functions of the above mentioned clutch members.

To hold the driving member or arbor *d* for the purpose of controlling the moment of actuation of the starter, as well as to permit the rewinding of the spring or springs *e*, I provide said arbor with a brake rim *k* concentric with the rims *g i* positioned therebetween, having acting thereon a friction pawl *l* normally seated against the stop *l'* carried by the plate *a*, by the spring *l²* to normally set said pawl so as to lock the arbor *d* through the resistance offered to the springs *e* in their effort to rotate the driven member *f*. It will be observed that when force is applied to said pawl so as to drive it against the stop *l'*, the said pawl will prevent any rotation of the arbor *d* and that when this pawl is drawn away from said stop and against the tension of said spring *l²*, the said driving member or arbor will be permitted to rotate freely. The pawl *l* therefore, constitutes with its coöperating brake rim, the holding means for the driving member, the releasing means for said pawl consisting of a flexible connection or pull *m*, extending to a bell crank lever or any other desired mechanism located adjacent to the driver's seat. It will be observed by this construction that the power required to start the device will be merely that necessary to overcome the normal friction between the pawl *l* and its brake rim *k*, and the tension of the spring *l²*, thus requiring but a slight exertion to trip the starter; and that immediately upon the release of the pull *m* the spring *l²* will tend to immediately restore the pawl to its set position and lock the driving member.

Having described the mechanism for applying the spring power to the driving member and the means controlling the moment of application of said power, I will now proceed to the description of the mechanism for rewinding the spring after the actuation of the device. In the connection in which a device of this character is used it is essential that a spring motor for the starter be rewound from the engine in connection with which it is used. Under normal conditions this rewinding means must be inoperative, and it must be so actuated as to immediately rewind the spring when the engine has been once started. Furthermore, such means must be so controlled as not to exhaust any of the spring energy when starting the engine, and not to place so great a load upon the engine, during the winding operation, as might result in the engine stopping after the spring energy had been exhausted and before the spring had been rewound. In the invention, as shown in the drawings, this

rewinding mechanism is shown as consisting of a reciprocating friction pawl n , constructed like the pawl h and adapted to engage the brake rim g , the said pawl being set and caused to bear against the stop n' , by means of the spring n^2 . Acting against the pawl n is an oscillatory lever o actuated by the eccentric p upon the driven member, said lever o being provided with an anti-friction roller o' engaging said eccentric or cam. By this construction the spring n^2 normally draws the pawl n toward the stop n' to set the pawl in the locked position upon the rim g , the oscillating lever o forcing the entire pawl forwardly, carrying with it the entire drum c (which carries the rim g) thus serving to rewind the spring from the driven member. The pawl h in addition to offering the resistance absorbing the reaction of the spring when the starter is actuated, acts as a holding pawl to take up the movement imparted to the drum by the rewinding mechanism. It will be observed that the degree of rotation of the drum under each rotation of the driven member is comparatively small, and by a powerful leverage, thus requiring but small force applied during a continuing interval to accomplish the entire rewinding of the spring. This alone would relieve the engine of a considerable load in starting, as the rewinding mechanism could be so designed as to require from six to eight hundred engine revolutions, or even more, to accomplish the rewinding of the spring. But I prefer to supplement the conservation of energy in rewinding by gearing down by an intermittent movement such as is secured by the eccentric p , thus not only reducing the actual load at all times during the rewinding interval, but eliminating the load altogether during a substantial proportion of each revolution of the engine. The interval during which the engine is under no load from the rewinding mechanism may be governed entirely by the contour of the eccentric p , although I prefer to use a disk eccentric, as shown in the drawings, for securing a gradual feeding movement, and an interval of rest equaling that of the interval of feeding, with each revolution.

The mechanism described would act continuously while the engine is running were not means provided for making said rewinding mechanism inoperative when the spring has been properly wound or tensioned. This means preferably consists of the bell crank lever q one arm of which is adapted to be projected into the path of the pawl n to act as a stop to hold this pawl out of the operative range of the lever o , the other arm thereof being adapted to be engaged by a tappet r carried by a star wheel s the teeth of which project adjacent to the rims g and k , which rims carry tappets $g' k'$

adapted to rotate this star wheel in either direction according to which disk is being rotated. To prevent the locking of the star wheel by a simultaneous engagement therewith by both tappets I provide each said tappet $g' k'$ with a spring which normally presses it into a position where it will engage the said star wheel and at the same time permit it to recede out of the path of the star wheel under such a condition. It will be observed that by the construction above described, not only will the rewinding mechanism be thrown out of operation by the tappet r , but that the moment of such operation will be controlled by the number of rotations of the star wheel under the tappet g' ; and the normal position of the tappet r will be governed by the number of rotations of the star wheel by the tappet k' when the arbor d is rotated by the springs in starting the engine. Hence, assuming that when the spring is at zero, the tappet r is set in that extreme position shown in the drawings, the rewinding drum will be turned six times before the holding arm of the bell crank lever q will prevent the return of the pawl n , and thus prevent the further winding movement. Hence by making the tappet r adjustable relative to the star wheel s , I may arbitrarily vary the number of rotations of the drum c in rewinding, and thus control the power which may be developed for starting purposes. This adjustment is desirable as giving such an effective range to a starter, as to permit its adaptation to engines of varying H. P. For example, assuming that the two springs shown in the drawings will develop, when wound by six revolutions of the drum, sufficient power to start a 30 H. P. engine, the starter may be adapted to a 10 H. P. engine by winding the springs by three revolutions of the drum, or to a 20 H. P. by winding it four or five revolutions as desired, to insure a sufficient safety factor. This adjustment means consists of a pin r' carried by the tappet r and adapted to seat in any of a series of sockets s' in the star wheel s , said tappet being provided with means exposed externally of the plate a , as the handle r^2 whereby the said tappet may be drawn forwardly sufficiently to disengage the stud r^2 from its socket s' rotated to the desired extent and reset in its adjusted position. Any other desired means of adjusting the tappet r' may be employed, however; or if desired, no means of adjustment may be provided, although I prefer to embody such in starters for general use, as distinguished from starters made for a particular type or style of machine.

In automobile appliances, it is desirable to provide safety factors which will prevent a disarrangement of parts, or loss of efficiency by careless or unskilled operators. In start-

ing the engine, under normal conditions the driver would hold the pull *m* forwardly a sufficient period to insure the starting of the engine, or an exhaustion of the spring in the 5 effort to do so. Others, however, might merely consider the pull *m* as a trip mechanism and give only one jerk to the pull member *m*, and thus upon the release of said member, accomplish the restoring of 10 the holding pawl *l* before the spring has had an opportunity to turn the engine over a sufficient number of times. To obviate this possibility of difficulty, I provide a latch member *l*² adapted to hold the pawl *l* in 15 operative immediately upon the release of said pawl by means of the pull *m*, means being provided as the tappet *s*² on the star wheel *s*, whereby said latch member will be released to permit the resetting of the pawl *l* 20 under its spring *l*² when the engine has been turned over the number of times predetermined by the location of the tappet *r*. The tappet *s*² has a fixed relation to the star wheel *s* the interval at which the pawl *l* 25 will be reset, being constant.

In gas engine practice, many conditions arise in which an engine fails to start even when properly turned over, such as the failure of a spark, or an improper mixture; so 30 that it is desirable to provide manually operative means whereby the engine may be started in case the spring motor of the starter fails to accomplish this result. Such a means is afforded in my starter by the hand 35 crank *t* having the impact coupling *t*¹ adapted to engage a cooperating impact coupling *t*² on the driven member, the spring *t*³ acting to normally disengage these coupling members. The arbor *d* is made 40 hollow to accommodate these coupling members and this spring.

In starting cranks there is the ever present danger of a "kick-back" from the engine due to a premature firing of the charge or 45 excessive compression before ignition and to eliminate this difficulty, I provide as a safety factor the pawl *u* which is normally seated in the locking position against the stud *u'* by the spring *u*² said pawl acting 50 upon the brake rim *k*. This pawl being normally set in the locking position offers a resistance to the return movement of the driving member or arbor *d* equaling the force applied thereto, thus permitting the 55 free rotation of said member in one direction while at all times preventing its return movement. The "kick-back" from the engine would tend to impart a reversal in the direction of rotation of the member *f*, 60 through said member being normally coupled to the driving member *d*, except when running at a higher speed than said member in the forward direction, but such rotation is prevented by the pawl *u*.

65 To permit a perfect understanding of the

operation of the various pawls, in the combination, it is necessary to clearly understand the mode of operation of this pawl which is not obvious. Any such pawls having a recess therein passing over a brake rim, which approximates in width the width of said rim allowing for the curvature thereof, will with the slight tilting of the pawl, cause the forward lower edge of the recess and the rear upper edge thereof to clamp 70 upon the rim. This tilting of the pawl is accomplished by placing a stop toward the bottom thereof and applying a light spring to the pawl above this stop. It will thus be observed that the pawl is normally tilted 75 in one direction holding it normally in the set position. If force be applied toward the pawl so that this force will be directed against the stop, the member through which the force is applied will be absolutely checked 80 by the resistance of the stop, through the pawl. If, however, force be applied to the pawl in the opposite direction, it will move the pawl away from its stop, tensioning the spring slightly, and the member through 85 which the force is applied encountering no resistance will rotate freely, the spring always pulling the pawl back toward its normal position. In other words, under the conditions last above named, the member 90 through which the force is applied, as a brake rim, will slide freely through the recess in the pawl unseating said pawl through the force applied thereby. Reversing the conditions, as in the case of the 95 pawl *j*, said pawl if connected to a movable member instead of a fixed resistance, the force applied thereto in the direction toward the spring holding it in the set position will apply the force exerted to the 100 movable member. If, however, this movable member is itself traveling at a greater rate of speed than the member applying force, it turns with the application of the force and the abutment against which the 105 pawl will overcome the tilting action of the spring, thus releasing the pawl and causing it to travel freely upon the member tending to apply the force. The third position arising 110 in connection with these pawls, is that found in the pawl *n*. A pawl having been set by means of its spring and the fixed abutment, it must follow that if you substitute for the fixed abutment a moving abutment traveling toward the pawl and 115 acting below the spring, power may be applied through the pawl to the brake rim, the spring acting on said pawl to hold the pawl set and immediately when the force from the moving abutment ceases, returning 120 the pawl to a new, set position. To summarize, when force is applied to a pawl by its brake rim in the direction toward the spring normally setting the same, the pawl will be 125 locked relative to its brake rim and said 130

brake rim and the member controlled thereby will be held against movement; or if said pawl be carried by a movable member said member will be moved. Inversely, 5 however, if the pawl itself be movable, power applied thereto from the same side thereof as its spring, will transmit the force to its brake rim.

The operation of the herein described 10 starting device is substantially as follows, assuming the springs to be at zero. Under this condition, it would be necessary to start the engine manually. The driver would first force the handle *t* inwardly until the 15 couplings *t'* engage the couplings *t''* on the driven member. By turning the crank in the usual manner, the driven member *f* would be turned to the right, Fig. 1, and to the left, Fig. 2 to turn the engine over. 20 The pawl *l* under such conditions would hold the arbor or driving member *d* stationary, the pawl *j* running idly upon its rim *i* with the rotation of the member *f*. In case 25 the engine should fire prematurely or "kick-back" from any other reasons whatsoever, the pawl *u* would prevent any movement of the driving member *d* under this force, notwithstanding the fact that the member *f* would be coupled to the said driving member *d* by the pawl *j* engaging the rim *i*. 30 Hence, the entire force of the reaction from the engine would be absorbed by the said pawl and the said driving member preventing any "kick-back" whatever upon the 35 hand crank *t*. If the charge, however, should be ignited properly, the driven member *f* will rotate entirely independently of the driving member *d*, the pawl or clutch member *j* running idly upon its rim *i*. The 40 engine thus running free so far as the starter is concerned, it would immediately begin to wind the springs *e* in the following manner:—The eccentric *p* will impart one direct and return oscillation to the lever *o* 45 with each revolution of the engine, and would impart a partial revolution to the drum *c* through the pawl *n* in the manner above described. With each rotation of the 50 drum *c* the tappet *g'* carried by the rim *g* out of the operative range of the various pawls would engage the star wheel *s* and turn it by successive stages with successive revolutions of said drum until the tappet *r* 55 carried thereby engages the bell crank lever *q* and force the holding or locking arm thereof inwardly until it holds the said pawl *n* against return movement, thus permitting the subsequent oscillations of the lever *o* without having any winding effect upon the 60 springs. It has been pointed out that this not only results in the rewinding of the drum by the application of small power through the reducing lever system, but at the same time causes the springs to be re- 65 wound by an intermittent movement. The

spring having been completely rewound, the 70 starter is then in condition to be used to mechanically start the engine from the driver's seat. As the springs are being rewound the pawl *h* upon the rim *g* holds the 75 said drum against return movement under its springs, the pawl *l* upon the rim *k* of the driving member preventing the rotation of said member under said springs during this operation and until it is desired to start 80 the engine.

Assuming that a stop is made, and the 85 engine shut down, to start the engine it is merely necessary for the driver to actuate the pull *m* which will release or trip the holding pawl *l*, thus permitting the springs to rotate the driving member or arbor *d*. This arbor being normally locked by the 90 pawl *j*, to the driven member *f*, the rotation thereof will turn the engine over the desired number of times as determined by the position of the tappet *r* relative to its star wheel. If the charge should be ignited when the 95 engine has been turned over once, the driven member *f* would run free, relative to the driving member *d* in the same manner as described in connection with the starting of the engine when hand cranked. The pawl *h* when the tripping or holding member *l* is released, absorbs all of the reaction of 95 the spring.

As the driving member *d* is rotated under its spring, the tappet *k'* carried thereby, reverses the direction of rotation of the star wheel *s*, permitting the spring *n²* to restore 100 the bell crank lever *q* to the position shown in the drawings, and bring the pawl *n* within the operative range of the lever *o*, thus positioning these parts so as to start the rewinding thereof with the continued rotation 105 of the engine shaft. As the pull *m* is advanced to release the pawl *l*, the latch member *l²* drops behind said pawl and holds it in its released or tripped position until the 110 stored energy in the springs is exhausted, the continued rotation of the star wheel *s*, however, bringing the tappet *s²* into engagement with said latch member *l²* when the driving member *d* has been rotated a predetermined number of revolutions, disengaging 115 said latch from said pawl and permitting said pawl to set and lock under its spring *l²*.

It will be observed that aside from the 120 whir incidental to the unwinding or uncoiling of a spring, the starter above described will be practically noiseless, and that the construction and arrangement of the various pawls is such as to cause them to exert their 125 braking action at any point whatever of their brake rims thus preventing said rims getting such a lead under power, as could brake or strip any of the parts. Not only are the parts employed few in number, but they are so assembled as to make it impos- 130

sible for them to get out of order, and any wear upon the various locking devices would be incidentally compensated for by variance in the angle of the tilt thereof under the 5 spring controlling the pawl.

It is not my intention to limit the invention to the precise details of construction shown in the drawings, it being apparent that such may be varied without departing 10 from the spirit or scope of the invention.

Having described the invention, what I claim as new and desire to have protected by Letters Patent, is:—

1. A starter for internal combustion engines embodying therein a spring actuated driving member, a driven member, an automatically actuated clutch operating solely by friction carried by one of said members and engaging the other when said driving 20 member is operative, said clutch being inoperative when said driving member is locked, whereby said driven member will be rotated with said driving member and may rotate independently thereof, means normally locking said driving member, means whereby said locking means may be released, and a re-winding mechanism operative from 25 said driven member.

2. A starter for internal combustion engines embodying therein a spring actuated driving member, a driven member, an automatically actuated clutch operating solely by friction carried by one of said members and engaging the other when said driving 30 member is operative, said clutch being inoperative when said driving member is locked, whereby said driven member will be rotated with said driving member and may rotate independently thereof, means normally locking said driving member, means whereby said locking means may be released, a re-winding mechanism operative from 35 said driven member, and automatically operating means for making said rewinding mechanism inoperative when the spring has been 40 rewound.

3. A starter for internal combustion engines embodying therein a spring actuated driving member, a driven member, an automatically actuated clutch operating solely by friction carried by one of said members and engaging the other when said driving member is operative, said clutch being inoperative when said driving member is locked, 45 whereby said driven member will be rotated with said driving member and may rotate independently thereof, means normally locking said driving member, means whereby said locking means may be released, a re-winding mechanism operative from said driven member, automatically operating means for making said rewinding mechanism inoperative when the spring has been 50 rewound, and means whereby the operative

moment of said last mentioned means may 65 be varied to vary the tension of the spring.

4. A starter for internal combustion engines embodying therein a spring actuated driving member, a driven member, an automatically actuated clutch operating solely 70 by friction carried by one of said members and engaging the other when said driving member is inoperative, said clutch being inoperative when said driving member is locked, whereby said driven member will be 75 rotated with said driving member and may rotate independently thereof, means normally locking said driving member, means whereby said locking means may be released, a rewinding mechanism operative from said 80 driven member, automatically operating means for making said rewinding mechanism inoperative when the spring has been rewound, means actuated by said driving member whereby said last mentioned means 85 may be made inoperative to start the rewinding operation and means actuated by said rewinding mechanism whereby said last mentioned means will be restored to normal to limit the winding operation. 90

5. A starter for internal combustion engines embodying therein a spring actuated driving member, a driven member, a friction clutch carried by one of said members and engaging the other when said driving member is inoperative, said clutch being inoperative when said driving member is locked, whereby said driven member will be rotated with said driving member and may rotate independently thereof, means normally locking said driving member, means whereby said locking means may be released, a rewinding mechanism operative from said 95 driven member, automatically operating means for making said rewinding mechanism inoperative when the spring has been rewound, means actuated by said driving member whereby said last mentioned means may be made inoperative to start the rewinding operation, means actuated by said 100 rewinding mechanism whereby said last mentioned means will be restored to normal to limit the winding operation, means temporarily holding said locking means in the released position and means automatically 105 releasing said locking means to permit its restoration to its locked position when the spring energy is exhausted. 110

6. A starter for internal combustion engines embodying therein a spring drum having a circumferential brake rim thereon, a spring actuated driving member mounted within said drum, a friction clutch engaging said rim and holding it against movement in one direction, while permitting its movement in the other direction, a driven member, a friction clutch carried by one of said members and engaging the other when said 120 125

- driving member is operative, said clutch being inoperative when said driving member is locked, whereby said driven member will rotate with said driving member and may 5 rotate independently thereof, means normally locking said driving member, means whereby said locking means may be released and a rewinding mechanism operating upon said brake rim. 70
- 10 7. A starter for internal combustion engines embodying therein a spring drum, means holding said drum against rotation in one direction and permitting its rotation in the other direction, a spring actuated driving member mounted within said drum comprising an arbor having thereon a plurality of concentric circular brake rims, a friction clutch acting upon the outer of said rims, to normally hold said driving member 75 against rotation under its spring, a driven member, a friction clutch carried by and rotatable with, said driven member and adapted to engage said driving member, when said driving member is rotated in one 80 direction and to be disengaged therefrom when said driven member revolves at a speed greater than the speed of said driving member, means whereby said locking clutch may be disengaged from said rim and a rewinding mechanism operative from said driven member and acting upon said spring drum. 85
- 15 8. A starter for internal combustion engines embodying therein a spring drum having a circumferential brake rim thereon, a spring actuated driving member mounted within said drum, a friction clutch engaging said rim and holding it against movement in one direction, while permitting its movement in the other direction, a driven member, a friction clutch carried by one of said members and engaging the other when said driving member is operative, said clutch being inoperative when said driving member is locked, whereby said driven member 90 will rotate with said driving member and may rotate independently thereof, means normally locking said driving member, means whereby said locking means may be released and a rewinding mechanism operating upon said brake rim, comprising a friction clutch member mounted upon said rim, means normally setting said clutch member upon said rim and means intermittently reciprocating said friction clutch member 95 when said clutch is set. 100
- 20 9. A starter for internal combustion engines embodying therein a spring drum having a circumferential brake rim thereon, a spring actuated driving member mounted within said drum, a friction clutch engaging said rim and holding it against movement in one direction while permitting its movement in the other direction, a driven member, a friction clutch carried by one of said 105 members and engaging the other when said 110
- 25 10. A starter for internal combustion engines embodying therein a spring drum, means holding said drum against rotation in one direction and permitting its rotation in the other direction, a spring actuated driving member mounted within said drum, comprising an arbor having thereon a plurality of concentric circular brake rims, a friction clutch acting upon the outer of said rims to normally hold said driving member against rotation under its spring, a driven member, a friction clutch pivotally connected at the bottom thereof with said driven member, a spring attached to said driven member and acting upon said last 115 named friction clutch to set it upon the rim of said driving member whereby said driven member will be rotated in one direction by said driving member and will be automatically disengaged therefrom when said driven member revolves at a speed greater than the speed of said driving member, means whereby said locking clutch may be disengaged from said rim and a rewinding mechanism operative from said driven member and acting upon said spring drum. 120
- 30 11. A starter for internal combustion engines embodying therein a spring drum, means holding said drum against rotation in one direction and permitting its rotation in the other direction, a spring actuated driving member mounted within said drum, comprising an arbor having thereon a plurality of concentric circular brake rims, a friction clutch acting upon the outer of said rims to normally hold said driving member against rotation under its spring, comprising a member having a recess therein straddling said rim, an abutment against which said member is adapted to be forced by said 125 130

rim; and a spring normally tilting said member to set it upon said rim, a driven member, a friction clutch pivotally connected at the bottom thereof with said driven member, a spring attached to said driven member and acting upon said last named friction clutch to set it upon the rim of said driving member whereby said driven member will be rotated in one direction by said driving member and will be automatically disengaged therefrom when said driven member revolves at a speed greater than the speed of said driving member, means whereby said locking clutch may be disengaged from 10 said rim and a rewinding mechanism operative from said driven member and acting upon said spring drum.

12. A starter for internal combustion engines embodying therein a spring drum, means holding said drum against rotation in one direction and permitting its rotation in the other direction, a spring actuated driving member mounted within said drum, comprising an arbor having thereon a plurality of concentric circular brake rims, a friction clutch acting upon the outer of said rims to normally hold said driving member against rotation under its spring, comprising a member having a recess therein straddling said rim, an abutment against which said member is adapted to be forced by said rim, and a spring normally tilting said member to set it upon said rim, a driven member, a friction clutch pivotally connected at the bottom thereof with said driven member, a spring attached to said driven member and acting upon said last named friction clutch to set it upon the rim of said driving member whereby said driven member will be rotated in one direction by said driving member and will be automatically disengaged therefrom when said driven member revolves at a speed greater than the speed of said driving member, means whereby said locking clutch may be disengaged from said rim, a trip latch adapted to automatically hold said locking member in the released position when said last named means are actuated, means actuated by said driving mechanism for automatically releasing said latch member when the spring is exhausted, and a rewinding mechanism operative from said driven member and acting upon said spring drum.

13. A starter for internal combustion engines embodying therein a spring drum having a circumferential brake rim thereon, a spring actuated driving member mounted within said drum, a friction clutch engaging said rim and holding it against movement in one direction while permitting its movement in the other direction, a driven member, a friction clutch carried by one of said members and engaging the other when 60 said driving member is operative, said clutch

being inoperative when said driving member is locked, whereby said driven member will rotate with said driving member and may rotate independently thereof, means normally locking said driving member, 70 means whereby said locking means may be released, and a rewinding mechanism operating upon said brake rim, comprising a friction clutch member loosely mounted upon said rim, means normally setting said clutch member upon its rim, an eccentric carried by said driven member, a lever oscillated thereby and adapted to intermittently feed said last mentioned friction clutch member forwardly during a portion of each revolution of said driven member, an oscillating bell crank lever one arm of which is adapted to be interposed in the path of said friction clutch member to prevent the return movement thereof and make said lever 80 inoperative, a star wheel mounted between said brake rim and said driven member, means carried by said brake rim and said driving member respectively, for alternately turning said star wheel in opposite directions, and a tappet carried by and rotatable with, said star wheel, adapted to engage the other arm of said bell crank lever when said star wheel is rotated by said driving member, and to disengage said arm when said star wheel is rotated by said brake rim. 90

14. A starter for internal combustion engines embodying therein a spring drum, means holding said drum against rotation in one direction and permitting its rotation in the other direction, a spring actuated driving member mounted within said drum, comprising an arbor having thereon a plurality of concentric circular brake rims, a friction clutch acting upon the outer of said rims to normally hold said driving member against rotation under its spring, comprising a member having a recess therein straddling said rim, an abutment against which said member is adapted to be forced by said rim, and a spring normally tilting said member to set it upon said rim, a driven member, a friction clutch pivotally connected at the bottom thereof with said driven member, a spring attached to said driven member and acting upon said last named friction clutch to set it upon the rim of said driving member whereby said driven member will be rotated in one direction by said driving member and will be automatically disengaged therefrom when said driven member revolves at a speed greater than the speed of said driving member, means whereby said locking clutch may be disengaged from said rim and a rewinding mechanism operating upon said brake rim, comprising a friction clutch member loosely mounted upon said rim, means normally setting said clutch member upon its rim, an eccentric carried by said driven member, a lever oscil- 120

lated thereby and adapted to intermittently feed said last mentioned friction clutch member forwardly during a portion of each revolution of said driven member, an oscillating bell crank lever one arm of which is adapted to be interposed in the path of said friction clutch member to prevent the return movement thereof and make said lever inoperative, a star wheel mounted between 10 said brake rim and said driven member, means carried by said brake rim and said driving member respectively, for alternately turning said star wheel in opposite directions, and a tappet carried by and rotatable 15 with, said star wheel, adapted to engage the other arm of said bell crank lever when said star wheel is rotated by said driving member, and to disengage said arm when said star wheel is rotated by said brake rim.

20 15. A starter for internal combustion engines embodying therein a spring actuated driving member, a driven member, an automatically actuated clutch member operating solely by friction carried by one of said 25 members and engaging the other when said driving member is operative, said clutch being inoperative when said driving member is locked, whereby said driven member will be rotated with said driving member and

may rotate independently thereof, means 30 normally locking said driving member, means whereby said locking means may be released, means constantly holding said driving member against a return movement, a hand crank rotatably mounted adjacent to 35 and adapted to be temporarily coupled to said driven member whereby the engine may be manually started independently of said driving member, and a rewinding mechanism operative from said driven member. 40

16. In a starter for internal combustion engines, a friction clutch mechanism comprising a circular brake rim and a clutch member adapted to engage same, comprising a block having a recess therein straddling said rim, a relatively fixed abutment, and a spring acting on said block to tilt it so as to cause the diagonally opposite corners of said recess to engage said rim, said tilting action being about said abutment. 45

In witness whereof, I have hereunto affixed my signature in the presence of two witnesses, this 9th day of June, 1910.

BERNHARD VOLKMAR.
